ONE-PIECE ADJUSTABLE STRAP

Max A. Benowitz, Kingston, N. Y.

Application April 1, 1935, Serial No. 14,085

4 Claims. (Cl. 2-237)

This invention relates to improvements in an adjustable strap construction and to the method of making the same. More particularly, this invention is directed to a one-piece adjustable garment-strap adapted to be used in connection with trousers, lumber jackets, melton coats, blouses, vests or other wearing apparel for taking up looseness in the garment and making it conform snugly to the wearer.

10 The adjustable garment-straps almost universally used prior to my invention in the manufacture of wearing apparel were of two-piece construction. The disadvantage of this type of construction is that a multiplicity of operations are required in the manufacturing process which greatly increase the cost of production.

15 In the two-piece construction, the making of the buckle-strap alone involves four operations, viz., cutting the cloth material to size, folding the longitudinal edges inwardly, single or double stitching the strap and finally, securing the buckle thereto. The making of the buckle-receiving strap involves even a larger number of operations. The cloth material which is to form the main portion of the strap and the lining therefor must first be cut to size. The two pieces are then placed in juxtaposition and stitched together along their marginal edges with the exception of one end which is left open to permit turning the strap inside out. The strap must then be turned inside out by hand and pressed, or stitched around its marginal edge. An end of each of the two separate straps thus formed is then threaded through respective appropriately positioned seams in the garment to which they are applied and stitched in place. Finally, the free end of the buckle-receiving strap must be threaded through the buckle. It is, therefore, apparent that the manufacture of a two-piece adjustable strap involves considerable cost due to the multiplicity of operations required.

20 It is an object of this invention to provide a one-piece adjustable garment strap, the manufacture of which involves relatively few operations as compared with the operations necessary to produce a two-piece strap suitable for the same or similar purposes.

25 Another object of this invention is to provide a single piece adjustable garment strap that has an improved appearance and is economical to manufacture.

30 A further object of the invention is the provision of a one-piece adjustable garment strap having a construction which affords convenience in adjustment.

Other objects and advantages will appear more fully from the following description taken in connection with the accompanying drawing, in which:

Figure 1 is a schematic side elevation view showing the method of stitching the lining to a series of cloth strips in a single continuous operation;

Figure 2 is a cross sectional view taken along line 2-2 of Figure 1;

Figure 3 is a side elevation view showing a series of cloth strips stitched by the method illustrated in Figure 1 to a continuous strip of lining material;

Figure 4 is an edge view of a completed strap;

Figure 5 is an edge view showing the strap of Figure 4 with the buckle in place;

Figure 6 is a plan view showing the adjustable strap with buckle attached, secured to a garment;

Figure 7 is a sectional view taken along line 7-7 of Figure 6;

Figure 8 is a sectional view showing a modified form of strap and buckle arrangement; and

Figure 9 shows in section a further modification of a one-piece strap construction.

Referring to the drawing, the reference numeral 10 designates a one-piece strap construction comprising a cloth strip 11 preferably of the same material as the garment to which the strap is to be attached and which is adapted to be stitched in a manner to be hereinafter fully described to a strip 12 of lining material of somewhat greater length than the cloth strip 11. The manner in which the cloth strip 11 is stitched to the lining 12 is schematically illustrated in Figures 1 and 2.

The table of a sewing machine is represented by line 13. The cloth strips 11 which have been previously cut to rectangular form of the desired length and width, are fed into a folder 14 which is adapted to fold the longitudinal marginal edges 15 of the strip upwardly and inwardly as shown in Figure 2. The lining material 12 may be fed from a reel (not shown) into a similar folder 16 positioned directly above the folder 14. The folder 16 is adapted to fold the longitudinal marginal edges 17 of the lining material downwardly and then inwardly as shown in Figure 2. Since the folding attachments 14 and 16 and the operations performed thereby are well known in the sewing machine art, it is not deemed necessary, for a clear understanding of the invention, to more fully illustrate or describe the same.

As the folded cloth strip 11 and the lining ma-

terial 12 emerge from their respective folders, they are stitched together along opposed longitudinal edges simultaneously by a pair of needles 18. The stitching operation is continued through 5 the strip 11 and lining 12, to the trailing end of the strip 11 and from that point on proceeds through the lining a predetermined distance to form a lining extension 19 of predetermined length. At this point, a second cloth strip 11 is 10 fed through the folder 14 and stitched to the lining 12 in a manner as above described. Thus, by a continuous operation, a series of cloth strips 11 are folded and stitched in spaced relation to the lining material. A portion of the continuous 15 strip thus produced is shown in Figure 3.

In order to obtain the proper spacing of the 20 cloth strips 11 along the lining material 12, a gage or index (not shown) may be used upon the sewing machine table 13 whereby the lining extensions 19, which are to form the buckle-anchoring 25 members, will all be of uniform length. Following the stitching operation, the lining 12 is cut at points 29, flush with one end of the several cloth strips 11 thereby severing the continuous strip into individual straps 10.

The lining extension 19 is then folded back 30 along the main body portion of the strap. The end of the strap 10, including the folded back lining extension 19, is then threaded through a buckle 21 of suitable design having a curved rim 35 and preferably an offset central bar or chape 22 extending across the rim. The lining extension 19 is then folded around the chape 22 and brought forward with its end in registration with the end 40 of the strap 10. The forward transverse member of the buckle rim is preferably provided with several fixed rearwardly extending tongues 23 adapted to engage the cloth strip 11 in a manner well known in the art.

40 The strap 10, with the buckle 21 attached, may then be secured to a garment as shown in Figures 6 and 7. The stitches of seam 24, which in this instance firmly unite portions 26 and 27 of the garment, also secure one end of the strap 10 in 45 place. These stitches also pass through both ends of the lining extension 19 so as to form a buckle-anchoring loop. The other end of the strap 10 is secured to the garment by the stitches of seam 25 which unite portions 27 and 28.

50 Adjustment of the strap 10, for the purpose of bringing the seams 24 and 25 toward each other, is accomplished by drawing the strap through the buckle to form a loop 29. When the adjustment has been made, releasing the strap 55 will allow the tongues 23 of buckle 21 to engage the cloth strip 11 thereby maintaining the adjustment. The strap may again be adjusted to its extended or to an intermediate position by slightly taking up the loop 29 so as to release 60 the strap from engagement with the tongues 23 and then turning the buckle slightly about the chape 22 as an axis so as to hold the tongues out of engagement with the strap, thereby allowing the strap to pass through the buckle to its extended or intermediate position.

65 Since the strap construction above described, does not have a free end as the straps of two-piece construction, the necessity of a keeper for holding the free end is obviated. A further advantage is that the strap will never become displaced from the buckle which often occurs with straps of the two-piece construction and is a constant source of annoyance to the wearer of the garment.

70 75 The modified construction shown in Figure 8

comprises a strap 30 and in this instance the lining material has been eliminated. The buckle 21, however, may be positioned upon the strap 30 in the same manner as above described. Since no lining is employed, a separate buckle-anchoring loop 31 of suitable material is provided looped about the chape 22.

75 A further modification of a single piece adjustable strap construction is shown in Figure 9. The arrangement shown in this figure is similar to that shown in Figure 8, with the exception that instead of using a fabric buckle-anchoring loop 31, a piece of elastic material 33 is employed. One end of the elastic strip 33 may be looped about the chape 22 of the buckle and stitched in place 15 as shown. The use of an elastic buckle-anchoring member 33 to a certain extent, relieves the strain on the buckle strap 32 and also allows the garment to conform more readily to the body 20 of the wearer. The strap constructions, as shown 25 in Figures 8 and 9, in each instance may be secured to appropriately positioned seams of the garment in a manner previously described.

30 It is apparent that the adjustable strap constructions above described obviate the necessity 25 for making provision for belt-supporting means, as belt loops, upon the garment. The usual belt is not required since the straps, by suitable adjustment, take up the looseness in the garment 30 making it conform snugly to the body of the 35 wearer thereby maintaining it in the desired position.

35 Although I have shown and described a particular adjustable strap construction and a specific method of making the same, it is to be understood that the same was for the purpose 40 of illustration and that many changes and modifications may be made by those skilled in the art without departing from the spirit and scope of the appended claims.

40 I claim:

1. A take-up strap for garments comprising a continuous outer strip and a continuous lining strip extending along the inner face of the outer strip, a buckle having a cross bar intermediate 45 its ends and openings at opposite sides of the cross bar through which the intermediate portion of the strap between its ends is threaded across the outer face of the cross bar, an anchor member forming a continuation of the lining 50 strip beyond the juxtaposed end of the outer strip, and being folded around the cross bar at its intermediate portion and having portions extended from the fold toward one end of the strip, and means for attaching said portions of the anchor member to the garment, and for attaching the opposite ends of the strap fixedly 55 to a garment at spaced points thereon.

2. A garment, a take-up strap therefor comprising a strip attached at spaced points to the 60 garment, a buckle adapted to be threaded upon said strip and movable therealong intermediate the said spaced points of attachment, and an anchor member secured to said buckle and extending toward one end of the strip and fixedly attached 65 to the garment, said strip being composed of relatively inelastic material and said anchor member being composed of elastic material.

3. As a new article of manufacture, in combination, a garment, a take-up strap therefor 70 comprising a continuous outer strip, and a continuous lining strip applied to the inner face of the outer strip, a buckle having a cross bar intermediate its ends and openings at opposite sides of the cross bar through which the inter- 75

mediate portion of the strap is threaded across the face of the cross bar, said lining strip being of greater length than the outer strip to thus provide an integral extension beyond the outer strip, which integral extension is folded back upon the outer strip, and then folded laterally away from the outer strip around said cross bar, and thence refolded back upon itself at the side of the first folded portion opposite that having the outer strip contiguous therewith, the said folded portions of the extension of the lining strip providing an anchor member, and attachment means intermediate the ends of the outer

strip and the garment and between the end portions of the folded portions of the extension of the lining strip and the garment.

4. An article of manufacture as claimed in claim 3, wherein the garment is provided with a seam and wherein the attachment means between one end of the outer strip, and the said folded portions of the extension of the lining strip comprises stitching common to said parts and connecting the portions of the garment forming the seam. 10
